BROOM WITH COMBINATION SUPPORT HOOK AND SCRAPER BLADE

Annie R. Thomas, 700 E. Emily,
Longview, Tex. 75601

Filed June 14, 1973, Ser. No. 370,184

Term of patent 14 years

Int. Cl. D4—01

U.S. Cl. D4—6

FIG. 1

FIG. 2

FIG. 3

FIG. 1 is a perspective view of a broom with a combination support hook and scraper blade;

FIG. 2 is another perspective view thereof, taken on a larger scale;

FIG. 3 is a perspective view thereof taken from the opposite end thereof;

FIG. 4 is a front elevational view thereof;

FIG. 5 is a side elevational view thereof;

FIG. 6 is a top plan view thereof.

The broom handle has been shown fragmentarily in FIGS. 2 and 3 for convenience of illustration.

I claim:

The ornamental design for a broom with combination support hook and scraper blade, substantially as shown and described.
